UNITED STATES PATENT OFFICE

2,504,892

CAR COUPLER POSITIONING AND SUPPORTING DEVICE

Vinton E. Sisson, Chicago, Ill., assignor to Standard Railway Equipment Manufacturing Company, Chicago, Ill., a corporation of Delaware

Application October 31, 1946, Serial No. 706,985

5 Claims. (Cl. 213—61)

1

This invention relates to coupler supporting and positioning devices for railway car couplers, and more particularly to means to swingably and resiliently support a railway car coupler in such manner that when the coupler is uncoupled, said coupler is maintained by the device in substantially the longitudinal central plane of the car, or in what is known in the trade as "coupling range."

More specifically the device comprises a coupler carrier pivotally supported at its ends by links which are pivotally, swingably, resiliently, and preferably adjustably supported intermediate their ends from a member adapted to be fixed to a railway car, such as a striking casting, as shown in the drawings. To provide such a device for so supporting a coupler and maintaining it when uncoupled within said "coupling range" is the principal object of the invention.

Broadly such a device is shown and claimed in my co-pending applications, Serial No. 706,982; Serial No. 706,983 and Serial No. 706,984, and the claims herein are accordingly restricted to the invention illustrated and described herein.

Another object of the invention is to provide such a cushioning coupler support and positioning device wherein should the cushioning means fail for any reason the device would nevertheless function as a coupler support and positioning device. In other words, should a spring break the coupler would still be swingably supported and be returned to "coupling range" by the device.

A further object of the invention is to provide such a cushioned coupler carrier and positioning device of the swing motion type wherein the cushioning means is not distorted during the swinging of the device.

A still further object of the invention is to provide such a cushioned coupler carrier and positioning device wherein provision is made for adjusting the height of the carrier and thereby the coupler to be supported thereby above the top of the rail without affecting the resiliency of said cushioning means.

The term "resilient means," as used in the specification and claims, is intended to cover springs, rubber, or any other resilient material. Most of these materials, if intermittently compressed to excess progressively lose their effectiveness, and, consequently, it is a further object of the invention to provide means to limit the compression of said resilient means.

In the drawings:

Figure 1 is a section on line 1—1 of Figure 2 showing one half of the device.

2

Figure 2 is a side elevation of the device.

Figure 3 is a view similar to Figure 1 of the whole device showing the coupler moved laterally.

Figure 4 is a view similar to Figure 1 showing the device as an emergency support and coupler positioning device.

Figures 5, 6 and 7 are, respectively, top, end and side views of the spring seat.

Figures 8 and 9 are, respectively, top and side views of the spring cap.

Figures 10 and 11 are, respectively, top and side views of the coupler support.

Figures 12 and 13 are, respectively, side and end views of the supporting links for the coupler carrier.

The coupler support and positioning device comprises two spaced rectangularly shaped plates 1 and 2, maintained in spaced relation by reinforcing webs 3 and 4. Web 4 extends adjacent the bottom of the spaced plates substantially from side to side thereof. Plates 1 and 2 are each provided with a rectangular central opening 5 therethrough, through which the shank 6 of the car coupler is longitudinally, laterally and vertically movable, as is common. Web 3 is channel-shaped in longitudinal section, and extends about the top and upper part of the sides of opening 5, and each end is provided with a laterally extending flange or shelf 7. The end portion of each flange or shelf is bifurcated and each bifurcated end formed into a bearing portion 8 adapted to receive a journal pin 9 which is in length almost equal to the distance between plates 1 and 2, and accordingly spans the space between the bearings 8—8. The coupler support suspending link is shown at 10 and comprises a link-like member, being threaded at its upper end and provided with a T-head at the other end providing trunnions 11—11 extending from opposite sides of said link. Intermediate the ends of the link 10 the link is upset, as at 12, and formed with an elongated eye 13 designed to surround the pin 9 and be pivotally supported thereon, but free to reciprocate thereon within the limits of eye 13. Mounted upon the link 10 above eye 13 is the spring seat 14, being circular in form, and provided with an axial hole 15 of a size to readily slip over the threaded end of the link 10. Flanges 16 project downwardly from the under surface of seat 14, they being spaced so as to occur on opposite sides of hole 15 so that link 10 may extend therebetween. (See Fig. 2.)

The lower edge of each flange 16 is formed with a semi-circular recess 17, the radius of which is substantially the same as that of the pin 9 so

that when the seat 14 is placed upon the link 10, recesses 17 may rest upon pin 9. Upon spring seat 14 is mounted the coil spring 18 which also surrounds the link 10, and on top of the spring about said link 10 is the washer-like spring cap 19, adjustably held in place thereon by the net 20.

The coupler carrier is indicated at 25 and is of generally channel-form with the ends thereof bifurcated so as to straddle the link 10 and formed into spaced bearing portions 26 to rest upon and be supported by the trunnions 11-11. Extending upwardly around the edge of each bifurcated portion is a web 27, the inner ends of which webs are spaced from each other a distance approximating the width of the shank 6 of the coupler. Carrier 25 is adapted to be positioned between the plates 1 and 2 and above web 4 so that when the carrier is suspended upon the links 10, as shown in Figures 1 to 4, said carrier may swing from side to side of the device between plates 1 and 2 and be resiliently, pivotally and reciprocably supported upon the pins 9 so that the coupler may move downwardly within the limits of the elongated slot 13, upwardly within the limits of the top of opening 5, and laterally within the limits of the side walls of opening 5. Any lateral movement of the coupler will, because it is carried by the carrier between ends of webs 27, move the carrier correspondingly through an arc about the axis of pin 9. The shorter the radius of this arc the higher the coupler will be elevated during its lateral movement, thereby more positively insuring the return of the coupler to normal central position by gravity should it be uncoupled while in a laterally moved position, such as shown in Figure 3. This is true regardless of whether the coupler is resiliently supported or not, and Figure 4 illustrates this possibility. In this view the whole spring assembly is shown as omitted from the link, with the upper edge of the eye 13 resting directly upon pin 9 and pivoting thereon. This view also illustrates the extreme simplicity of applying or replacing a spring to the device. In this position the device still functions as a coupler support and positioning device of the swing motion type. Therefore, if anything should happen to any or all of the parts providing the resilience to the support, the device would still function and save the car from being declared unfit for service.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

1. claim:

1. Means to swingably and resiliently support a coupler carrier from a member adapted to be fixed to a car and provided with spaced bearings at each end thereof, said means comprising journal pins each of which is adapted to engage respective bearings at each end of said member and span the space therebetween, a pair of links, each adapted to pivotally suspend one end of said carrier from respective ends of said member, a seat mounted upon each link and pivotally engaging said journal pin between said respective bearings, a cap mounted upon each link, resilient means between each seat and cap, means to hold said link, cap, resilient means and seat in operative rela-

tionship, said journal pin passing through an elongated opening in its respective link to provide means to limit the downward movement of said link without affecting the pivotal suspension of the carrier.

2. Means to swingably and resiliently support a coupler carrier from a member adapted to be fixed to a car and provided with spaced bearings at each end of said member, said means comprising journal pins each of which is adapted to engage respective bearings at each end of said member and span the space therebetween, a pair of links, each adapted to pivotally suspend one end of said carrier from respective ends of said member, each of said links having an elongated opening therethrough surrounding said journal pin between said respective bearings to limit the movement of said link; a seat mounted upon each link and pivotally engaging said journal pin between said respective bearings, a cap mounted upon each link, resilient means between each seat and cap, means to hold said link, cap, resilient means and seat in operative relationship, the relation of said journal and said elongated opening being such as to provide means to limit the downward movement of said link without affecting the pivotal suspension of the carrier.

3. In a device to swingably and resiliently support a coupler carrier from a member adapted to be fixed to a car and provided with spaced bearings, said device including a journal pin adapted to engage said bearings and span the space therebetween, a link adapted to pivotally suspend an end of said carrier from said member, a seat mounted upon said link and pivotally engaging said journal pin between said bearings, a cap mounted upon said link, resilient means about said link between said seat and cap, means to adjust the height of the carrier without affecting the tension of the resilient means, said journal passing through an elongated opening in said link to provide means to limit the downward movement of said link without affecting the pivotal suspension of the carrier.

4. In a device to swingably and resiliently support a coupler carrier from a member adapted to be fixed to a car and provided with spaced bearings, a journal pin adapted to engage said bearings and span the space therebetween, a link adapted to pivotally suspend an end of said carrier and having an elongated opening therethrough through which said journal pin extends, a seat mounted about said link and pivotally engaging said journal pin, a cap mounted upon said link, resilient means about said link, between said seat and cap, whereby the downward movement of the link is limited by the length of said elongated slot.

5. A structure as defined in claim 4 wherein said cap is adjustably mounted on said link whereby the height of said carrier in relation to said member may be varied.
